Gaston Ajello

UNITED STATES PATENT OFFICE.

GAETAN AJELLO, OF NEW YORK, N. Y.

RAILROAD CAR AND TRACK CONSTRUCTION.

Application filed September 11, 1923. Serial No. 602,125.

To all whom it may concern:

Be it known that I, GAETAN AJELLO, a citizen of the United States, residing at New York, in the county of New York and State 5 of New York, have invented an Improvement on Railroad Car and Track Constructions, of which the following is a specification.

The object of the invention is to provide 10 for railroad cars, irrespective of the elasticity of wood railroad ties, a comfortable, resilient, uniformly plane and noiseless travel; therefore a combination of an improved rigid track and cars carrying their 15 own means of elasticity, thereby eliminating the costly and irregular wood tie construction; in other words, there has always been the tendency to do away with the wood tie construction in order to considerably reduce 20 the expenses of maintenance and troubles inherent thereto, but such an elimination would be impossible were it not for the adaptation of elastic means embodied into the cars. (To take place of the elasticity of the wood ties.) The importance of 25 such combination is further obvious by citing that with the present wood tie cushioning, a wheel near the joint between two rails, while causing one rail to sag, drags 30 the other down by the joint connection, thereby creating such mechanical disturbances at track joints to necessitate frequent inspection and tightening of bolts, not to say that the ties themselves, unless removed 35 when defective, after usage, they cause a train to wobble in all directions and not travel in uniform, perfect plane position.

With such object in view, I provide an 40 improved rigid track construction in view of cushioning means applied into the wheels of cars between an inner and an outer or circumferential portion of the wheels proper.

On the accompanying sheet of drawings 45 forming a part of this specification,

Fig. 1 represents a cross section through the improved track construction,

Fig. 2 is a cross section through a railroad car wheel embodying its cushioning means,

Fig. 3 is a circumferential section, in plane development, through the cushioning means embodied into the car wheels.

Referring by numerals to the drawings, 1 represents the rail, 2 its rigid bed construction to which it is anchored by anchors 55 and provided with expansion joints occur-

ring simultaneously with the rail joints. The surface between the rails is finished smooth sloping towards a gutter 4 provided with drains 5 at intervals. The head of 60 the rail is provided with a drip 6 that serves also to interlock plastic waterproof material 7 to prevent rusting and infiltration of water at joint between rail and track bed, this improvement being very valuable 65 especially for elevated railroad track and at bridge track construction.

8 represents the outer circumferential part of the wheel coming in contact with the rail and 9 the inner portion of the wheel. 70 Both portions of the wheel in the direction of facing each other, concentrically, terminate with flanges 10, which, while designed for the necessary stresses imposed, serve to receive filling material 11, preferably a heat 75 insulator the type of asbestos or one of its late combinations called asbestos wood; the space between the outer and inner portions is occupied by the cushioning means 12 consisting of elastic material the like of rubber, provided preferably with deformations 13 for more efficient resiliency.

The outer and inner portions of the wheel are connected together by means of peripheral, circular, concentric bands 14 of resilient 85 material preferably rubber or the like, held fast against the two portions of the wheel by means of similar, concentric metallic bands 15 through bolts 16. The contact between the elastic bands 14 and the metallic parts 90 of the wheel is through concentric bands 17 of heat insulating material.

In order to further insure against an accidental possibility of the outer portion of 95 the wheel displacing itself too far, laterally, in relation to the inner portion of the wheel, metallic guards 18 may be placed at intervals radially; but in case of electric railway, these guards, through a springy universal joint 19 would keep arm 20 in contact with 100 the outer portion of the wheel without touching its outer cushioning means, thus forming a continuous resilient electric contact between the two metallic parts of the wheel 105 for the necessary negative electrical discharge to the rails.

The brake drum for the car wheels may be incorporated onto the inner portion of the wheel or separately as at 21, acting on 110 the same wheel axle *xx*.

I claim:

1. In a railroad car and track construc-

tion, a wheel consisting of an outer and an inner portion concentrically spaced in relation to each other, embodying in the concentric space between them flanges projecting from each portion toward the other portion, heat insulating means between each set of flanges and cushioning means between the insulating means.

2. A wheel as specified in claim 1 in combination with an electrical conductor secured at the inner portion of the wheel and extending toward the outer portion, said conductor to serve simultaneously as a guard against ultimate lateral displace-

ment of one portion of the wheel in relation 15 to the other.

3. In railroad car and track construction a wheel as specified in claim 1 comprising lateral, peripheral elastic means outside the cushioning means. 20

4. In railroad car and track construction a wheel as specified in claim 1 comprising lateral or peripheral elastic rings between the two portions of the wheel and insulating rings between each of the portions 25 of the wheel and the outer elastic peripheral means.

GAETAN AJELLO.
